UNITED STATES PATENT OFFICE

149,393

DESIGN FOR A MEASURING COMB

Richard Wheeler and Robert F. Cozad,
Des Moines, Iowa

Application September 7, 1946, Serial No. 133,144

Term of patent 3½ years

(Cl. D86—8)

To all whom it may concern:

Be it known that we, Richard Wheeler and Robert F. Cozad, citizens of the United States and residents of Des Moines, in the county of Polk and State of Iowa, have invented a new, original, and ornamental Design for a Measuring Comb, of which the following is a specification, reference being had to the accompanying drawing forming part thereof, in which:

Fig. 1 is a top view of a measuring comb, showing our new design;

Fig. 2 is a side view thereof;

Fig. 3 is an enlarged end view looking toward the right in Fig. 2; and

Fig. 4 is an enlarged sectional view taken along the line 4—4 in Fig. 2.

The side of the comb not disclosed is substantially the same as the side shown in Fig. 2.

We claim:

The ornamental design for a measuring comb, substantially as shown and described.

RICHARD WHEELER.
ROBERT F. COZAD.
